UNITED STATES PATENT OFFICE.

DANIEL REISER, OF CLEVELAND, OHIO.

FOLDING AND STACKING MACHINE.

Specification of Letters Patent. Patented June 17, 1919.

1,307,148.

Application filed July 9, 1917. Serial No. 179,353.

To all whom it may concern:

Be it known that I, DANIEL REISER, a citizen of the United States, residing at Cleveland, in the county of Cuyahoga and State of Ohio, have invented a certain new and useful Improvement in Folding and Stacking Machines, of which the following is a full, clear, and exact description, reference being had to the accompanying drawings.

10 This invention relates to apparatus for use in book-binding establishments and especially to a machine for folding and stacking booklets, pamphlets and such like in a particularly efficient and rapid manner.

15 The object of the invention is an improved apparatus of this type whereby the booklets may be automatically folded and stacked with a minimum expenditure of time and labor and to this end I have devised a machine

20 whose operations are entirely automatic and are controlled by the folders or booklets themselves, the folding, and stacking devices remaining idle in the absence of a folder to operate upon. In the specific embodiment

25 of the invention illustrated herein the apparatus is shown in combination with a stitching or stapling machine for receiving and removing the pamphlets and booklets therefrom and automatically folding and

30 stacking the same in a rapid and efficient manner.

For a better understanding of the above noted and other features of this invention which will hereinafter appear reference may be had to the accompanying drawings illustrating one embodiment of this invention wherein Figure 1 is a side elevation of the improved machine set up for operation with a standard stitching and stapling machine; Fig. 2 is a top plan view of the apparatus; Fig. 3 is a sectional view taken on the line 3—3 of Fig. 1 certain parts being omitted for convenience in illustration; Fig. 4 is a similar sectional view taken on the line 4—4 of Fig. 1; Fig. 5 is a detail view of one of the parts; Fig. 6 is another detail view thereof; and Fig. 7 is a perspective view of the knife frame.

Referring to the drawings where like numbers refer to similar parts throughout, a standard stitching and stapling machine is designated generally by the numeral 1, and the improved apparatus of the present invention is designated generally by the numeral 2, it being understood that the folding and stacking machine 2 receives the

folders from the stitching machine 1 as they are stitched and released therefrom.

The framework of the folding machine 2 comprises four standards 3 resting on any suitable base not illustrated in the drawings. The standards 3 at either end of the machine are bridged at the top by horizontal bars 4, these cross bars preferably being formed integral with the standards 3. Intermediate the ends of the standards 3 and below the cross bars 4 are bracing rods or bars 5, these also being preferably formed integrally with the standards. Intermediate the cross bars 4 and 5 there are additional 70 bracing bars 6 which extend lengthwise of the machine and at right angles to the bars 4 and 5 and are also formed integral with the standards 3, the standards 3 and cross bars 4, 5 and 6 thus forming a rigid framework for the support of the different mechanisms.

Extending rearwardly from the machine and to a point adjacent the forward end thereof there is mounted a saddle 7, this saddle being of the usual V-shaped form with its apex turned upward and being in alignment with the saddle of the stitching and stapling machine 1. The saddle may be conveniently supported by means of a 85 bracket 8 extending upwardly from the rear cross bar 5 and at its front end by a similar upright standard not illustrated in the drawings. The saddle 7 is also provided with the usual endless conveyer belts 9 located on each 90 side thereof slightly below the apex and traversing the exterior of the saddle in the forward direction but returning underneath the saddle. The conveyers 9 are carried by suitable small pulleys 10 suitably journaled 95 near the apex of the saddle 7 and also by larger and additional pulleys 11 mounted on a drive shaft 12, the latter being journaled at one end in a yoke 13^a mounted on a standard 13 carried by the front cross bar 100 5 and at the other end in a member 13^b carried by a bracket projecting outwardly from the cross bar 5. The pulleys 10 extend through vertical openings formed on the sides of the saddle 7 as illustrated for transferring the conveyer from the exterior to the interior of the saddle. An additional continuous conveyer 14 is illustrated on the rear end of the saddle which is mounted to traverse the apex thereof and to drive a gripping idler pulley 15, the latter being loosely mounted on an adjustable arm 16 and being

in engagement with the conveyer 14 and continuously driven thereby. The arrangement is such that the pulley 15 may be adjusted to different distances from the stitching and 5 stapling machine 1 to accommodate the apparatus to different folder lengths. Mounted just above the saddle 7 and parallel therewith are two folding rollers 17 and 18, these rollers being conveniently journaled 10 in the end cross bars 4. These rollers are adapted to be continuously driven and are geared together to cause one to rotate counterclockwise while the other rotates clockwise, this gearing comprising intermeshing 15 pinions 19 on the forward ends thereof. Extending lengthwise of the machine is a cross bar 20 which is carried by the transverse cross bars 4 and throughout the length of this cross bar are mounted a series of pulley 20 supporting brackets 21, the latter carrying small pulleys which coöperate with the roller 18 to carry a series of horizontally disposed conveyer tapes 22. In the specific embodiment shown there are illustrated 25 seven of these tapes shown in dotted lines in Fig. 1. These tapes are spaced apart a predetermined distance to accommodate therebetween apparatus hereinafter described. Mounted on the top of the supporting framework is a receiving receptacle 30 or bin 23 mounted lengthwise of the machine and bridging the cross bars 4. The receptacle designated generally by 23 comprises a pair of end standards 24 which rest on the cross bars 4 and carry from the upper ends thereof horizontally disposed brackets 24^a. The standards 24 and brackets 24^a are bridged respectively by pairs of cross pieces, 35 25 and 25^a extending lengthwise of the machine, and each pair of cross pieces carries a series of vertically disposed panels 26 and 26^a, this arrangement forming a rectangular bin or receptacle which is open both at the top and the bottom for the reception and 40 removal of folders or booklets. The conveyer tapes 22 as illustrated extend beneath the receptacle and are adapted to receive the folders from the saddle 7 and convey them to a position from which they are elevated 45 to the receptacle. Mounted on the lower ends of the panels 26 is a series of fingers 27 which are pivoted thereto for pivotal movement in a vertical direction from the horizontal but limited in their downward movement to prevent movement below the horizontal. As illustrated in Figs. 5 and 6 this is accomplished by the rear end of the finger engaging a suitable shoulder 28 upon the lower end of the panel. Each panel 26 has 50 fixed to the side thereof a spring 29 which has its free end bent at right angles thereto and passing through an opening 30 in the panel in the path of the finger 27, the arrangement being such that the finger 27 engages the spring 29 in its upward pivotal

movement and is caused thereby to be forced back to the normal or horizontal position when the actuating force is removed. The set of panels 26 adjacent to the rollers 17 and 18 is provided with a series of guards 31 which are mounted on the lower ends thereof in alinement with the horizontally disposed fingers 27 whereby the folders or booklets are guided and directed on to the conveyers 22 in their travel to a point beneath the receptacle 23. The guards 31 extend above and adjacent to the rollers 17 and 18 and therefore are adapted to engage the folders when they emerge upwardly from between the rollers and guide them onto the conveyer 22. 75 Additional guards 32 are mounted at intervals along a cross piece 33, the latter extending lengthwise of the machine and resting at its rear end on the cross bar 4 and being fixed at its forward end to a bracket 34 which 80 in turn is carried by the front cross bar 4. As illustrated in Figs. 3 and 4 these guards 32 extend over the roller 18 and in proximity to the periphery of the roller 17, these guards or guides 32 being curved or bent 85 downwardly in the manner illustrated to insure the folders following the prescribed path over the roller 18 and conveyer tapes 22. 90 Mounted beneath the saddle 7 and adapted to play in and through the apex thereof are 95 a multiplicity of vertically reciprocating knives 35, these knives being mounted on a frame 36 having vertically disposed guide bars 37, the guide bars 37 in turn being carried in suitable vertically disposed guideways in the brackets 38 extending inwardly 100 from the cross bars 5. The guide bars 37 are provided with vertically elongated slots 39 for the passage therethrough of one of the conveyer belts 9. The guide bars 37 also 105 are provided on one side thereof with rack teeth for mesh with spur gears 40 mounted on a shaft 41 extending longitudinally of the machine and journaled in the cross bars 5, only one of these pinions 40 being apparent in the drawings. The shaft 41 on its forward end carries a spur pinion 42 which meshes with a larger pinion 43 journaled on a depending bracket carried by the front cross bar 5. The gear 43 in turn meshes 110 with a vertically reciprocating rack 44 which is mounted in vertical guideways 44^a formed on a casting integral with the cross bar 5. Mounted on one of the cross bars 6 extending longitudinally of the machine is a bracket 115 45 which has formed therein an elongated vertical guideway for the reception of a vertically reciprocable rack 46 which carries a stacker head 47. The bracket 45 may be secured to the bar 6 by means of a bolt 45^a. 120 The stacker head 47 comprises a transverse rod 48 and a series of pairs of horizontally disposed fingers 49 adjustably mounted thereon. Each pair of fingers 49 is positioned between two adjacent conveyer tapes 130

22 and is adapted to be reciprocated vertically to a position above the conveyer belts or tapes and fingers 27 or to a position below the conveyers, the arrangement being such that the fingers clear both the conveyers and the panels 26 and 26^a during the reciprocation.

The stacker head 47 is adapted to be reciprocated vertically by a shaft 50, the latter 10 having a pinion thereon in mesh with the rack 46 (Fig. 4). The shaft in turn is oscillated from the shaft 41 through a sprocket and chain gearing, the sprockets being designated respectively 51 and 52.

15 The drive for the various mechanisms is obtained from a driving motor, as shown an electric motor, mounted on the bracket 54 projecting forwardly from the machine and carried by the front cross bar 5. A 20 drive shaft 55 mounted above the motor shaft is journaled in the standard 13 and the yoke 13^a carried by the cross bar 5 and this shaft 55 is geared to the motor through a gearing 56. The inner end of the shaft 25 55 carries a bevel pinion 57 which meshes with a similar pinion on the shaft 12 for driving the pulleys 11 and the continuous conveyer belts 9 and 14. Intermediate its 30 ends the shaft 55 carries a pinion 58 which meshes with the large idler 59 carried on a bracket depending from the cross bar 4. The idler 59 in turn meshes with small spur pinion 19 on the roller 18, this small pinion in turn meshing with a similar pinion on 35 the roller 17. The rollers 17 and 18 and conveyer tapes 22 are thereby continuously driven from the motor and counter shaft 55. The idler 59 is mounted on a countershaft 60 and on the outer end of the shaft 60 is 40 fixed a small pinion 61, which in turn meshes with a large spur gear 62 loosely mounted upon the reduced end forming the shaft 18^a of the roller 18, the shaft 18^a projecting forwardly of the machine and suitably journaled in the cross bar 14. Secured to the 45 hub of the gear 62 is a cam 63 coöoperating with a roller 65 journaled on a stud 64 carried by the rack 44. By means of this rotating cam and the roller 65 the rack 44 50 is periodically caused to assume its maximum height. A suitable roller 66 mounted on a stub axle fixed to one of the cross bars 55 is provided on the opposite side of the rack from the cam 63 and roller 65 to receive the thrust and to maintain the rack in proper alignment. In order to maintain the rack 44 in the elevated position a pawl 67 60 is provided which is adapted to engage a shoulder 68 on the upper end of the rack, the pawl 67 being urged into engaging relation at all times by gravity. The pawl 67 is pivoted to the bracket 34 mounted on the top of the cross bar 4 and has a downwardly depending spring arm 69, the spring arm 69 65 projecting downwardly through a slot in the

apex of the saddle 7 and in the path of movement of the folders while being conveyed by the conveyer belts 9.

The operation of the machine is as follows: The folders or brackets on being 70 stitched or stapled are received from the stapling machine 1 onto the saddle 7. The idler pulley 15 and the conveyer 14 initiates the movement of the folder along the saddle and movement is continued through the medium of the conveyer belts 9 to the limit of movement. The belts are run at a considerable speed and cause a rapid movement of the folder or booklet. The forward end of the folder or booklet engages the spring arm 75 69 depending downwardly in its path and bends the same to the dotted position illustrated in Fig. 1. For preventing the rebound of the folder a resilient member 70 is mounted in the path of movement of the folder and is caused to engage the rear end of the folder when the limit of movement is reached, the member 70 being mounted on an adjustable arm 71 to accommodate the apparatus to different folder lengths. 80 Upon the bending of the spring arm 69 and thereby putting the same under tension the pawl 67 is caused to be disengaged from the shoulder 68 of the rack 44 or is caused to move out of the path thereof to the dotted 85 position shown leaving the rack 44 free to recede to the lowermost position while the cam 63 is making one turn. In order to facilitate the disengagement of the pawl 90 67 from the tooth or shoulder 68 the arrangement is such that the cam 63 slightly raises the rack 44 out of engagement with the pawl 67 at each turn thereof. Upon the release of the rack 44 the same falls by 95 gravity to its lowermost position, this movement being hastened by the weight or mass of the stacker head 47 which also falls by gravity and causes the elevation of the racks 100 37 together with the knife frame 36. It is understood that the combined weight of 105 the rack 44 and the stacker head 47 which are geared to move in the same direction is sufficient to overbalance the knife frame 110 36. The lower position of the stacker head 47 and the elevated position of the knives 115 35 are illustrated in Fig. 4 and in this position it is noted that the stacker head fingers 49 are positioned below the upper sides of the conveyer tapes 22 to permit the folders or booklets to be positioned thereover by the 120 tapes. The knives 35 engage the middle of the folders and urge them upward between the folding rollers 17 and 18 which are rotated at a rapid rate. The guards or guides 31 and 32 direct the folded booklets onto the 125 tapes 22 as heretofore set forth and the booklets are conveyed to a point in register with the stacking bin 23. It is noted that the panels 26^a extend downwardly to a point 130 below the level at the tapes 22 and thereby

- arrest the forward movement of the folders. The stacker head 47 and knives 35 remain in the positions illustrated in Fig. 4 only while the cam 63 is making one turn, this time being entirely sufficient to remove the folder from the saddle 7 to the position above the stacker head 47. When the cam 63 makes one complete turn it again engages the roller 65 and elevates the rack 44 and the stacker head 47 against the force of gravity and this elevation of the stacker head 47 carries the folder up into the stacking bin 23 past the fingers 27, these fingers serving to retain the folders therein. The booklets are thus folded and the air expelled therefrom in an efficient manner and the same are stacked automatically within the bin 23 to be removed at the leisure of the operator. It should be noted that the tripping arrangement is such that the pawl 67 cannot be released until the rack is elevated slightly by the cam 63, the pull of the spring arm 69 under tension being insufficient to cause disengagement of the pawl. Each folder therefore is insured the time of a complete turn of the cam for transfer from the saddle to the bin.
- For limiting the downward movement of the rack 44 a bumper 72 is provided which comprises a pad of yielding material 73, as of leather, a bolt 74 being provided through the support 72 for adjusting the vertical position of the pad. By adjusting the downward movement of the rack 44 the upward movement of the knives 35 may be limited to any degree. It is noted that the knives 35 may be adjusted to different points along the frame 36, the frame 36 being provided with a series of apertures throughout its length for the reception of fastening screws. The rear knives on this frame may therefore be entirely removed or adjusted to different distances from the rear end of the machine thereby varying the distance the folder has to travel in coming from the machine 1 before it reaches the knives and rendering unnecessary an increase in speed of the machine to clear the knives out of the way of the advancing folders. It is noted too that while the force of gravity is used in lowering the rack 44 and the stacker head 47 it is obvious that other and positive actuating means may be used instead. It is also noted that the stapling and stitching machine 1 is for illustrative purposes only and that the present invention is capable of embodiment in machines for various uses and in combination with various machines.
- In accordance with the requirements of the patent statutes I have set forth one embodiment of my invention in the specific and particular manner illustrated but it is understood that the claims hereto annexed are not

to be limited to the specific devices and apparatus set forth except as is specifically recited therein or is rendered necessary by a consideration of the prior art.

Having thus described my invention, what I claim is:—

1. In an apparatus of the type described the combination of a saddle, means for conveying a folder along said saddle, reciprocating knives underneath said saddle, means for locking said knives against movement, means for receiving said folder, and means controlled by the arrival of a folder for unlocking said knives.

2. In an apparatus of the type described the combination of a saddle, means for conveying a folder along said saddle, reciprocating knives underneath said saddle, folding and stacking devices mounted above the level of said saddle, and means controlled by said folder for reciprocating said knives and operating said stacking devices.

3. In a device of the character described in combination, a conveyer for paper sheets, a knife supported adjacent to said conveyer and adapted to be moved transversely thereof to remove sheets therefrom, means for receiving the sheets from said knife, conveying means for receiving the sheets from said receiving means, means for locking said knife against movement, and means controlled jointly by the arrival of a booklet and by the movement of said second conveying means for unlocking said knife.

4. In an apparatus of the type described the combination of the saddle, means for conveying a folder or booklet along said saddle, folding and stacking devices mounted above the level of the saddle, transferring means disposed between said saddle and said stacking means, reciprocating knives underneath said saddle for delivering said folder or booklet to said transferring means, and means controlled by the movement of said folder or booklet along said saddle for reciprocating said knives and operating said stacking means.

5. In an apparatus of the type described in combination, a conveyer for folders or booklets, a bin for receiving said folders or booklets, conveying means disposed between said conveyer and said bin for transferring folders or booklets from one to the other, reciprocating devices for transferring folders or booklets from said conveyer to said conveying means, reciprocating devices for transferring folders or booklets from said conveying means to said bin, operative connection between said conveying means, power operative devices for actuating one of said means, means for locking said first reciprocating means against movement and mechanisms for unlocking said means controlled jointly by the arrival of a folder or

pamphlet and by the arrival of said second reciprocating means at a predetermined phase of its operation.

6. In an apparatus of the type described, 5 the combination of the saddle, means for conveying folders or booklets longitudinally along said saddle, a bin for receiving said folders or booklets, conveying means disposed between said saddle and said bin for 10 conveying said folders or booklets transversely of their lengths from said saddle, a stacking head coöoperating with said bin and said conveying means, reciprocating devices underneath said saddle for transferring said 15 folders or booklets from the saddle to the conveying means, and means controlled by the movement of said folders or booklets longitudinally along said saddle for reciprocating said knives and operating said stacking 20 head.

7. In an apparatus of the type described the combination of a saddle, means for conveying folders or booklets along said saddle, a bin mounted above the level of the saddle 25 for receiving said folders or booklets, a plurality of horizontally disposed continuous conveyer tapes underneath said bin and adapted to receive the folders or booklets from said saddle, a vertically reciprocating 30 stacking head adapted either to assume a position in the bin or a position below the conveyer tapes, vertically reciprocating devices underneath said saddle for transferring the folders or booklets from said saddle to 35 said conveyer tapes, means for reciprocating said knives and said stacking head in opposite directions and means controlled by the movement of the folders or booklets along said saddle for causing the operation of said 40 reciprocating means.

8. In an apparatus of the type described the combination of a saddle, means for conveying folders or booklets along said saddle, a pair of folding rollers mounted above said 45 saddle, a bin mounted above the level of the saddle for receiving said folders or booklets, a plurality of horizontally disposed continuous conveyer tapes underneath said bin and adapted to receive the folders or booklets 50 from said rollers, a vertically reciprocating stacking head adapted either to assume a position within the bin or a position below the conveyer tapes, vertically reciprocating devices underneath said saddle for transferring the folders or booklets from said saddle to 55 said rollers, means for reciprocating said knives and said stacking head in opposite directions and means controlled by the movement of the folders or booklets along said 60 saddle for causing the operation of said reciprocating means.

9. In an apparatus of the type described the combination of a saddle, means for conveying a folder along said saddle, a pair of

folding rollers mounted above said saddle, 65 a receiving bin mounted above the level of the rollers, a plurality of horizontally disposed continuous conveyer tapes beneath said bin and adapted to receive the folder from said rollers, a vertically reciprocating 70 stacking head adapted to assume either a position within the bin or beneath the conveyer tapes, reciprocating knives mounted beneath said saddle and adapted to be elevated to transfer the folder transversely of 75 its length from said saddle to said rollers, gearing devices between said reciprocating knives and said stacking head whereby the knives and the stacking head are caused to move in opposite directions, means operating 80 intermittently to elevate said stacking head, means for normally maintaining said stacking head in the elevated position within the bin, and means controlled by the movement of said folders along said saddle to release 85 said retaining means.

10. In an apparatus of the type described the combination of a saddle, means for conveying a folder along said saddle, a pair of folding rollers mounted above said saddle, a 90 receiving bin mounted above the level of the rollers, a plurality of horizontally disposed continuous conveyer tapes beneath said bin and adapted to receive the folder from said rollers, a vertically reciprocating stacking 95 head adapted to assume either a position within the bin or beneath the conveyer tapes, reciprocating knives mounted beneath said saddle and adapted to be elevated to transfer the folder transversely of its length from 100 said saddle to said rollers, gearing devices between said reciprocating knives and said stacking head whereby the knives and the stacking head are caused to move in opposite directions, said knives being overbalanced 105 by said stacking head, means operating intermittently to elevate said stacking head and lower said knives, means for retaining said stacking head in the elevated position 110 within the bin when no folder is present, and means controlled by the movement of said folder along said saddle to release said retaining means.

11. In an apparatus of the type described, 115 the combination of a V-shaped saddle having means thereon for conveying a folder or booklet longitudinally there-along, a pair of folding rollers parallel arranged with reference to said saddle and mounted above the apex thereof, a stacking bin mounted 120 slightly above the level of the rollers, a plurality of horizontally disposed conveyer tapes, said tapes being disposed underneath said bin and traversing one of said rollers, a vertically reciprocating stacking head 125 adapted to assume an elevated position within said bin or a lowered position below said conveyer tapes, reciprocating knives mount-

ed beneath said saddle and adapted to be thrust through the apex of said saddle, a system of gearing disposed between said knives and said stacking head whereby said 5 knives and said stacking head are caused to move in opposite directions, a reciprocating rack geared to said stacking head to move therewith, an intermittently operating cam for elevating said rack, said rack having a 10 shoulder thereon, a pawl adapted to engage said shoulder and thereby retain said stacking head and said rack in the elevated position, said pawl having a spring arm projecting downwardly in the path of the folders 15 moving along said saddle, and a motor for driving said cam, said rollers and said tapes.

12. In an apparatus of the type described, the combination of a V-shaped saddle having means thereon for conveying a folder or 20 booklet longitudinally there-along, a pair of folding rollers parallel arranged with reference to said saddle and mounted above the apex thereof, a stacking bin mounted slightly above the level of the rollers, a 25 plurality of horizontally disposed conveyer tapes, disposed underneath said bin, and traversing one of said rollers, a vertically reciprocating stacking head adapted to assume either an elevated position 30 within said bin or a lowered position below said conveyer tapes, reciprocating knives mounted beneath said saddle and adapted to be thrust through the apex of said saddle, a system of gearing interposed between said 35 knives and said stacking head whereby said knives and said stacking head are caused to move in opposite directions, a reciprocating rack geared to said stacking head to move therewith, said rack having an actuating 40 roller thereon, a rotating cam for engaging said roller and elevating said rack, said rack having a shoulder thereon, a pawl adapted to engage said shoulder and thereby retain said stacking head and said rack in an ele- 45 vated position, said pawl having a spring arm projecting downwardly in the path of the folders moving along said saddle, adjustable means for limiting the downward movement of said rack, and a motor for driving said cam, said rollers and said tapes.

13. In an apparatus of the kind described, in combination, a frame work, a saddle, means for conveying a folder or booklet longitudinally therealong, a pair of folding rollers journaled on said frame and disposed adjacent to said saddle, a plurality of conveyer tapes for ejecting folders or booklets therefrom, a reciprocating knife coöperating with said saddle and adapted 55 to insert a folder between said rollers, operative connections between said head and knife causing them to operate alternately, power means for advancing said head, means for locking said head against retraction, means operated by the arrival of a 60

booklet or pamphlet for unlocking said head, and means for preventing such unlocking except at a predetermined phase in the movement of said head.

14. In an apparatus of the type de- 70 scribed the combination of a frame work, a V-shaped saddle, said saddle being inverted and having continuous conveyer belts thereon for conveying a folder or booklet longitudinally therealong, a pair 75 of folding rollers journaled on said frame and disposed above the apex of the inverted saddle, a stacking bin mounted above the level of said rollers but horizontally displaced therefrom, a plurality of continuous 80 conveyer tapes underneath said bin and traversing one of said rollers, a vertically reciprocating stacking head coöperating with said tapes and said bin for receiving the folder or booklet from the tapes and 85 transferring them to said bin, a reciprocating knife frame having knives thereon disposed beneath the apex of said saddle and adapted to project therethrough to engage folder on the line of fold, a system of gear- 90 ing interposed between said knife frame and said stacking head comprising reciprocating racks and intermeshing gears whereby a movement of the stacking head in a 95 vertical direction causes the movement, of the knife frame in the opposite direction, adjustable means for limiting the downward movement of said stacking head, stationary guiding devices disposed above said rollers for guiding the lifted folders or folded 100 booklets onto said conveyer tapes, means within said bin and disposed near the bottom thereof for retaining the stacked folders therein when the stacking head is lowered, a vertically reciprocating shaft connected 105 with said system of gearing for movement with the stacking head, means for limiting the downward movement of said reciprocating shaft, a rotating cam for elevating said shaft, the said shaft having an actuating 110 roller thereon disposed in the path of the rotating cam, a pawl mounted on said frame-work and adapted normally to engage a projection on said shaft for retaining the same in the elevated position, said 115 pawl having a spring arm projecting downwardly into the path of the folders or booklets moving along said saddle for releasing said pawl and thereby causing the elevation of the knives and the lowering of the stack- 120 ing head, an adjustable retaining means adapted to grip the rear end of the folder in its actuating position, and power means for driving said cam, said folding rollers and said continuous conveyer tapes.

15. In an apparatus of the type de- 125 scribed, the combination of a supporting frame work, a horizontally disposed V-shaped saddle, conveyer belts adapted to carry a folder along said saddle, two fold- 130

ing rollers mounted above said saddle with the opening between said rollers in vertical alinement with the apex of said V-shaped saddle, a plurality of horizontally disposed 5 continuous conveyer tapes, said tapes being laterally displaced from each other, and carried at one end by one of said rollers and at the other end by a series of small pulleys carried by a cross bar mounted on said 10 frame work, a stacking bin or receptacle mounted above said tapes, said bin having spring pressed pivoted fingers mounted at intervals along the lower parts of two opposite walls and projecting inwardly for 15 retaining the stacked booklets therein, a vertically reciprocable head comprising a plurality of horizontally disposed stacking fingers, said stacking fingers alternating with said conveyer tapes and adapted to 20 assume a position therebelow, said stacking fingers being adapted to assume an elevated position above said spring pressed fingers, a vertically reciprocable frame carrying a plurality of vertically disposed 25 knives, said knife frame being disposed below said saddle and said knives being adapted to project upwardly through the apex of said saddle, said stacking head and said knife frame comprising vertically disposed 30 racks, gearing devices between said racks comprising a countershaft whereby they are caused to move in opposite directions, a vertically disposed driving rack having an

actuating roller thereon and geared to said countershaft, a second shaft disposed below 35 said roller and carrying an actuating cam for engaging said roller and lifting said driving rack, said driving rack having a shoulder on one side thereof, a pawl having a spring arm and normalized in the path of 40 said shoulder for retaining said driving rack in the elevated position, said spring arm projecting downwardly through the apex of said saddle in the path of the folders, and means for driving said cam 45 shaft, said rollers and said conveying tapes and belts.

16. In a device of the character described, the combination of a pair of upright sides defining a bin, a plurality of spaced parallel conveyer tapes passing beneath said bin, a vertically reciprocating head located beneath said bin and having spaced members adapted to pass between adjacent tapes, means for feeding separate booklets or 50 pamphlets singly to said tapes, means for reciprocating said head to elevate said pamphlets or booklets into said bin, and catches carried by the bin walls adapted to receive said booklets or pamphlets from 55 said head and prevent the same from falling back upon said tapes.

In testimony whereof I hereunto affix my signature.

DANIEL REISER.
